UNITED STATES PATENT OFFICE.

WILLIAM HENRY SIGLEY, OF SYLVAN GROVE, KANSAS.

FUNNEL.

Application filed September 11, 1925. Serial No. 55,768.

The present invention has reference to funnels and more particularly to a funnel especially designed for filling barrels having openings in their ends or sides.

- 5 The primary object of the invention is to provide a funnel so constructed that the same may be readily supported on the barrel in a manner to insure against movement thereof while the barrel is being filled.
- 10 A further object of the invention is to provide a funnel which may be cheaply constructed, the same being formed by a single stamping operation whereby the blank may be readily formed.

- 15 With the foregoing and other objects in view which will appear as the description proceeds, the invention resides in the combination and arrangement of parts and in the details of construction hereinafter described 20 and claimed, it being understood that changes in the precise embodiment of the invention herein disclosed, may be made within the scope of what is claimed, without departing from the spirit of the invention.

25 Referring to the drawing:

Figure 1 is a side elevational view illustrating a funnel constructed in accordance with the invention as positioned for filling a barrel through a filling opening in the head thereof.

Figure 2 is a sectional view through the forward portion of the funnel.

Figure 3 is a sectional view taken on line 3—3 of Figure 1.

35 Figure 4 is a diagrammatic view illustrating the blank from which the funnel is constructed.

Referring to the drawing in detail, the reference character 5 indicates the body portion of the funnel which is formed preferably of sheet metal.

The blank forming the body portion has its side edges cut away as at 6 and 7, defining a bottom portion 8 and side walls 9, the edges 40 of the side walls 9 being brought into close engagement with the edges of the bottom 8

where they are soldered in such a way as to maintain the shape of the body portion or funnel.

In order that the body portion will be 50 further braced, the upper edge thereof is rolled as at 10 and reinforced by means of a wire 11. The edges of the blank are inclined as clearly shown by Figure 4 so that when the blank is bent in the formation of a 55 funnel, the funnel will have an inclined bottom inclined towards the opening 12.

Secured to the body portion at a point adjacent to the opening is a spout 13 which also tapers to accommodate the removable 60 spout 14 provided with a right angled extremity 15 to be used for filling a barrel from an end opening, while the barrel is resting on its side.

When the barrel is to be filled through an 65 opening in the side, the removable spout 14 is removed and the spout 13 positioned within the opening. A support 15 is secured to the body portion adjacent to the spout and engages the barrel at a point adjacent to the 70 filling opening thereof to relieve the spout of undue strain during the filling process.

At the rear of the body portion of the funnel is a leg member 16, which is in the form of a metallic bar having its ends secured 75 to opposite sides of the body portion, the intermediate portion of the bar being curved as at 17 to conform to the curvature of the barrel.

I claim:

A funnel including a blank formed of a length of sheet material having converging side edges and having cut out portions formed in its front and rear end edges, the cut out portions having curved lateral walls and curved inner walls, said blank adapted to be folded intermediate its side edges to provide side walls and a curved bottom, and said bottom having a discharge opening. 85

In testimony that I claim the foregoing as 90 my own, I have hereto affixed my signature.

WILLIAM HENRY SIGLEY.
